UNITED STATES PATENT OFFICE.

JOHN A. BEDWORTH, OF BOSTON, MASSACHUSETTS, ASSIGNOR TO F. S. WEBSTER COMPANY, OF SAME PLACE, NEW YORK, N. Y., CHICAGO, ILLINOIS, AND LONDON, ENGLAND.

DESIGN FOR A RIBBON-SPOOL FOR TYPE-WRITING MACHINES.

SPECIFICATION forming part of Design No. 34,403, dated April 23, 1901.

Application filed March 28, 1901. Serial No. 53,357. Term of patent 14 years.

To all whom it may concern:

Be it known that I, JOHN A. BEDWORTH, a citizen of the United States, residing at Boston, county of Suffolk, and State of Massachusetts, have invented and produced a new, useful, and original Design for a Ribbon-Spool for Type-Writing Machines, of which the following is a specification, reference being had to the accompanying drawings, forming a part thereof.

The leading feature of my design for a ribbon-spool for type-writing machines consists of a hub on the opposite ends of which are star-like plates which constitute the heads of the spool.

The ribbon-spool has a centrally-apertured hub e, provided at its opposite ends with plates f, which constitute the heads of the spool. Each head is shaped to present a series of radiating arms f', giving the head the configuration of a star, and as there are five arms a five-pointed star is represented. Each arm is shown as provided with a longitudinal rib or corrugation f'', extended inward from the extremity or point of the arm. The central aperture of the hub is shown at e'', Fig. 1.

Having fully described my design, what I claim, and desire to secure by Letters Patent, is—

The design for a ribbon-spool for type-writing machines, substantially as herein shown and described.

In testimony whereof I have signed my name to this specification in the presence of two subscribing witnesses.

JOHN A. BEDWORTH.
